UNITED STATES PATENT OFFICE.

SAMUEL K. PLANK, OF HOUSTON, TEXAS.

VEHICLE-SPRING.

1,227,307.

Specification of Letters Patent. Patented May 22, 1917.

Application filed June 17, 1916. Serial No. 104,275.

To all whom it may concern:

Be it known that I, SAMUEL K. PLANK, a citizen of the United States, residing at Houston, in the county of Harris and State 5 of Texas, have invented certain new and useful Improvements in Vehicle-Springs; and I do hereby declare the following to be a full, clear, and exact description of the invention, such as will enable others 10 skilled in the art to which it appertains to make and use the same.

This invention relates to vehicle springs, and more particularly to an elliptical vehicle spring wherein the inner leaf is 15 formed of one continuous piece, and has its ends curved inwardly into the ellipse formed by the spring and also to form a substantially oblong portion whereby the upper section of the elliptical spring may 20 move longitudinally independent of the lower section of the spring, or vice versa, and also to position the oblong portion and the curved portions of the ends of the inner leaf of the spring so that they will engage 25 the inner surface of the inner leaf and limit the compressing movement of the spring.

With the foregoing and other objects in view this invention consists in such novel 30 features of construction, combination and arrangement of parts as will be hereinafter more fully described, illustrated in the accompanying drawing and claimed.

In describing the invention in detail reference will be had to the accompanying drawing wherein like characters designate like and corresponding parts throughout 35 the several views, and in which:—

Figure 1 is a side elevation of a vehicle 40 spring constructed in accordance with this invention.

Fig. 2 is a side elevation of the inner leaf of a vehicle spring constructed in accordance with this invention, and

Fig. 3 is a view illustrating a semi-elliptical spring constructed in accordance with this invention.

Referring more particularly to the drawing, 1 designates the vehicle spring as an 50 entirety, which is composed of a plurality of leaves 2, as is ordinary in the construction of elliptical vehicle springs. The inner leaf 3 of the vehicle spring structure is constructed of a single piece of spring 55 steel, having its ends welded to form one continuous piece as clearly shown in Fig. 2

of the drawing. The portions of the inner leaf 3, which form the ends of the elliptical spring 1 are rolled or curved inwardly as shown at 4, and they are curved inwardly 60 into the ellipse formed by the spring, and further curved upwardly and downwardly as clearly shown at 5 to form loops or substantially oval-shaped portions 6, the ends of which extend toward and face portions 65 of the inner surface of the leaf 3.

The inner leaf 3 being constructed of spring steel will permit the upper section 7 of the elliptical spring 1 to move longitudinally a limited distance independent of 70 movement of the lower section 8, or vice versa.

The rolled or curved portions 4 of the inner leaf 3 face each other and are slightly spaced as clearly shown in the drawing. 75 Upon depression of the spring, these facing portions will, by engagement with each other tend to limit the compression movement of the sections 7 and 8 of the spring which compressing movement will further 80 be limited by the engagement of the ends of the substantially oval portion 5 with the inner surface of portions of the inner leaf 3.

In Fig. 3 of the drawing a modified form of the invention is shown which includes a 85 semi-elliptical spring leaf 20 which is constructed for use upon particular types of vehicles and which has its ends rolled as shown at 21 in an identical manner of the rolling or curving of the ends 4 of the inner 90 leaf 3 and a semi-loop or oval-shaped portion 22 is provided. The action of the semi-elliptical spring leaf 20 is identical with the action of one-half of the leaf 3. The modified form of the spring leaf may be attached 95 to a vehicle in any of the ordinary manners employed in mounting semi-elliptical springs.

In reducing the invention to practice, certain minor features of construction, combination and arrangement of parts may necessitate alterations to which the patentee is entitled provided such alterations are comprehended within the scope of what is claimed.

What is claimed is:—

In an elliptical vehicle spring structure, an innermost leaf formed of a single piece of spring steel having its ends connected, the portions of said innermost leaf forming 110 the end of the elliptical spring being curved inwardly into the ellipse formed by the

spring, said curved portions being spaced from each other for engagement upon compression of the spring for retarding the compressing movement of the spring, the 5 said portions of said inner leaf being further bent to form a loop positioned inwardly of the ellipse formed by the spring, whereby one section of the elliptical spring will be permitted a limited longitudinal 10 movement independent of the other section, the ends of said looped portions adapt-

ed for engagement with portions of the inner surface of the innermost leaf for further retarding the compressing action of the spring. 15

In testimony whereof I affix my signature in presence of two witnesses.

SAMUEL K. PLANK.
